UNITED STATES PATENT OFFICE.

EDWARD F. CALDWELL, OF NEW YORK, N. Y.

DESIGN FOR A PAPER-CUTTER.

41,423.

Specification for Design.

Patented June 6, 1911.

Application filed February 3, 1911. Serial No. 606,422. Term of patent 3½ years.

To all whom it may concern:

Be it known that I, EDWARD F. CALDWELL, a citizen of the United States, and a resident of the city of New York, borough of Manhattan, in the county and State of New York, have invented a new, original, and ornamental Design for Paper-Cutters, of which the following is a specification, reference being had to the accompanying drawing, forming a part thereof.

The figure is a plan view of a paper cutter showing my new design.

I claim:

The ornamental design for a paper cutter as shown.

EDWARD F. CALDWELL.
